United States Patent Office

Des. 220,507
Patented Apr. 20, 1971

220,507

TOY FIRE TRUCK BODY

Vernon A. Peterson, Minneapolis, Minn., assignor to
Tonka Corporation, Mound, Minn.

Filed June 25, 1970, Ser. No. 23,672

Term of patent 7 years

Int. Cl. D21—02

U.S. Cl. D34—15

FIG. 1

FIG. 2

FIG. 1 is a top front perspective view of a toy fire truck body showing my new design;

FIG. 2 is a top plan view thereof;

FIG. 3 is a left side elevational view thereof;

FIG. 4 is a front elevational view thereof; and

FIG. 5 is a rear elevational view.

I claim:

The ornamental design for a toy fire truck body, as shown.
